(57) **CLAIM**

We claim the ornamental design for a robotic toy, as shown and described.

DESCRIPTION

FIG. 1 is an isometric view, from the front right, of the robotic toy of a third embodiment having attachment ports and a midsection decoration;

FIG. 2 is an elevation view of the front of the robotic toy of the third embodiment;

FIG. 3 is an elevation view of the right side of the robotic toy of the third embodiment;

FIG. 4 is an elevation view of the left side of the robotic toy of the third embodiment;

FIG. 5 is a plan view of the top of the robotic toy of the third embodiment;

FIG. 6 is a plan view of the bottom of the robotic toy of the third embodiment;

FIG. 7 is an elevation view of the back of the robotic toy of the third embodiment; and,

FIG. 8 is an isometric view from the back left of the robotic toy of the third embodiment.

The broken lines in the Figures show portions of the robotic toy, which form no part of the claimed design.
